UNITED STATES PATENT OFFICE.

EDWARD J. DACEY, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

JACQUARD MECHANISM FOR LOOMS.

Application filed August 18, 1925. Serial No. 51,012.

To all whom it may concern:

Be it known that I, EDWARD J. DACEY, a citizen of the United States, residing at Worcester, in the county of Worcester and 5 State of Massachusetts, have invented a new and useful Jacquard Mechanism for Looms, of which the following is a specification.

This invention relates to improvements in 10 jacquard mechanism for looms and an object of the invention is to provide means for holding certain risers or hooks out of operative position while permitting the remaining hooks to be operated on in the usual 15 manner.

Not infrequently it happens that a loom is required to weave a lighter fabric than that for which it was designed and in order to prevent undue wear and reduce the cutting 20 of the cards it is desirable to make some provision for holding out of action those hooks which are not to be used. For instance, the jacquard mechanism may be designed for use with six frames but it may 25 be desired to use the same with but five frames, in which case the hooks corresponding to the sixth frame would be idle and should be held in inactive position. The usual type of needle employed in jacquards 30 has one end bent back on itself to form a U-shaped portion which passes through a guiding rod and is adapted to hold a spring located between the rod and a shoulder formed on the needle. It is a more particular 35 object of my invention to employ locking pins supported by the jacquard mechanism and so positioned as to pass through the bent ends of certain of the needles and hold the same out of active position. By means 40 of these pins I am enabled to convert a six frame jacquard into one of five frames without the use of specially formed needles.

With these and other objects in view 45 which will appear as the description proceeds, my invention resides in the combination and arrangement of parts hereinafter described and set forth in the claims.

In the accompanying drawings wherein I have shown one convenient form of my invention,

Fig. 1 is a vertical longitudinal section through the upper portion of a jacquard having my invention applied thereto,

Fig. 2 is an enlarged elevation of the spring box shown in Fig. 1, and 55

Fig. 3 is a horizontal section on line 3—3 of Fig. 2.

Referring to the drawings it will be seen that I have provided a jacquard frame 10 having a griff 11 provided with knives 12 which reciprocate vertically with the griff 60 to engage the hooks 13. One end of the jacquard is provided with a needle board 14 through which the ends of the needles 15 pass. A cylinder 16 positions the cards 65 17 which cooperate with the needles to move some of them and to leave others unmoved as the cylinder advances toward needle board 14. The opposite end of the jacquard is provided with a spring box 18 having 70 vertical rods 19 extending between the parallel sides 20 of the corresponding needles. Each needle is provided with a shoulder 21 and has a spring 22 located between the shoulder and the associated rod 19. Spacing wires 23 position the needles vertically. The matter thus far described is of common 75 construction and forms no part of my invention.

My improvements reside in the devices for 80 holding selected needles in inoperative position and in carrying out my improvements I extend the upper and lower walls 28 and 29, respectively, of the needle box 18 as shown in the drawings and provide the same 85 with slots 30 open at one end to receive locking pins 31. Said pins 31 are formed with heads 32 which prevent the same from falling through the slots 30 and are preferably 90 rectangular in cross-section, being thin 95 enough to pass through the bent portions 20 of the needle. As shown in Fig. 1 the upper pair of needles are locked in inactive position, the locking pins 31 passing through the bent ends thereof, the springs 22 holding the locking pins 31 in the slots 30 to prevent movement to the left thereof as shown in Fig. 1. As shown in the drawings the two hooks to the right of Fig. 1 are locked 100 in inoperative position but are spaced 105 slightly from the lower ends of the knives 12 to avoid contact with the latter as they rise and fall. The dotted lines in said Fig. 1 indicate the position the hooks would assume if they were unlocked but pushed back 105 by a blank space on the card. It is to be

understood that the locking pins are narrow enough to permit the ordinary operative movements of the needles without interfering with the same.

- 5 From the foregoing it will be seen that I have provided a very simple lock to cooperate with the usual form of needle to hold the same in inoperative position when desired. It will also be seen that the springs 10 usually employed in connection with the needles cooperate to hold the locking pins in the open slots 30 and that said pins are spaced sufficiently from the adjacent ends of the needles to permit normal operative movement of the latter.

Having thus described my invention it is apparent that changes and modifications may be made therein by those skilled in the art without departing from the spirit and 20 scope of the invention, and I do not wish to be limited to the details herein disclosed but what I claim is:

1. In a jacquard mechanism for looms having reciprocable knives, risers to cooperate with the same, and needles formed with bent ends and adapted to position the risers, the combination of a locking pin extending through the bent ends of selected needles to hold the same permanently in in- 30 operative position.

2. In a jacquard mechanism for looms having reciprocable knives, risers to be engaged by said knives, needles formed with bent ends and adapted to position the risers, 35 and springs normally holding the needles in normal position, the combination of locking means extending through the bent ends of the needles to hold certain of said needles out of normal position, the springs of the 40 selected needles holding the means against displacement in one direction longitudinally of the needles.

3. In a jacquard mechanism for looms

having reciprocable knives, risers to cooperate with the same, needles formed with 45 bent ends and adapted to position the risers, a spring box, and springs carried by the needles to hold the latter in normal position, the combination of locking pins to extend through the bent ends of selected needles to hold the latter out of normal position, said pins extending through open slots formed in portions of the spring box and being held in said open slots by the springs.

4. The combination in a jacquard mechanism for looms having risers, knives to cooperate with the same and needles movable longitudinally to position the risers, of a member extending transversely of the needles and engaging certain of the needles to 60 hold the same permanently in inoperative position to place the risers corresponding thereto in inoperative position with respect to the knives.

5. The combination in a jacquard mechanism for looms having risers, reciprocable knives to cooperate with the same, needles to position the risers, and spring to return the needles to normal position, of means supported in fixed position on the jacquard 70 mechanism and cooperating with certain of the needles to hold them permanently out of normal position against the action of the springs associated therewith.

6. In a jacquard mechanism for looms 75 having risers, reciprocable knives to cooperate therewith, needles to position the risers, and cards to cooperate with the needles to move certain of said needles, the combination of stationary means carried by the jacquard to hold selected needles beyond the 80 position to which they are moved by the blank spaces of the cards.

In testimony whereof I have hereunto affixed my signature.

EDWARD J. DACEY.
